UNITED STATES PATENT OFFICE.

CHARLES J. DIEGES, OF NEW YORK, N. Y.

DESIGN FOR A BADGE.

No. 40,000.

Specification for Design.

Patented May 25, 1909.

Application filed March 29, 1909. Serial No. 486,623. Term of patent 7 years.

To all whom it may concern:

Be it known that I, CHARLES J. DIEGES, a citizen of the United States, residing in the borough of Manhattan, city, county, and State of New York, have invented a new, original, and ornamental Design for a Badge, of which the following is a specification.

The nature of my design is fully represented in the accompanying drawing, to which

reference is made and which shows in elevation, a badge embodying my design.

I claim,

The ornamental design for a badge, as shown.

CHARLES J. DIEGES.
